GASIFICATION OF CARBONACEOUS SOLID FUELS

Earl L. Tornquist, Elmhurst, Ill., assignor to Northern Illinois Gas Company, Aurora, Ill., a corporation of Illinois

Filed Oct. 26, 1955, Ser. No. 541,582

19 Claims. (Cl. 48—197)

This invention relates to means and method or process by which a gas having a high heating value per cubic foot may be produced in an efficient and economical manner from carbonaceous solid fuels such as coal, char, lignite and the like. Such a gas is intended as a substitute for natural gas and should provide in the neighborhood of 1000 B.t.u. per cubic foot. A mixture of combustible gases in which 90% or more thereof comprises methane will be very satisfactory for this purpose.

One of the more generally accepted methods of obtaining methane from coal has embodied the steps of first generating a synthesis gas of carbon monoxide (CO) and hydrogen gas (H₂) and then passing the synthesis gas over a nickel catalyst at about 600° F. and 300 p.s.i.a. to produce the methane. However, care must be taken to be sure that the synthesis gas does not contain sulphur. Even small traces thereof will cause poisoning of the catalyst and purification is, therefore, a vital step in the process.

The synthesis gas was usually generated at temperatures in the range of 1600° F. to 3000° F. and the reaction is endothermic. This heat is usually supplied by burning coal with relatively pure oxygen, hereinafter referred to as "tonnage oxygen," since if air were used directly, the high nitrogen content of the synthesis gas would make it unsuitable for conversion to methane. Although the methanization step was highly exothermic, the heat of the reaction was liberated at around 600° F. so that it was too low to be used for the production of hydrogen and therefore a considerable amount of tonnage oxygen and coal consumed in supplying this heat was not efficiently used. At the same time, because the methanization step was highly exothermic, as witness the following equations typical of the reaction, means had to be provided to dissipate the reaction heat.

The reactions generally considered to take place in methanization are as follows:

- (1) 4CO + 8H₂ → 3CH₄ + 2H₂O + CO₂ + 285,000 B.t.u.
- (2) CO + 3H₂ → CH₄ + H₂O + 91,000 B.t.u.
- (3) CO₂ + 4H₂ → CH₄ + 2H₂O + 71,500 B.t.u.

In each reaction, it will be noted that four moles of synthesis gas are required to produce one mole of methane, and if the four moles are all hydrogen, one mole of CO₂ in addition is required.

The heat of reaction required for producing a mole of carbon monoxide is about twice that required for producing a mole of hydrogen. Since many of the reactions for forming methane require ratios of carbon monoxide to hydrogen different than in the synthesis gas resulting from the gasification reactions, a supplementary reaction such as the water gas shift method needs to be employed to obtain the proper ratio of carbon monoxide to hydrogen gas. It will thus be readily apparent from all these factors that it becomes expensive to produce a pipeline gas consisting principally of methane by this method. Moreover, the process is low in overall efficiency while the tonnage oxygen requirements are high.

Therefore a first and primary object of the invention is to provide a means and/or method for producing a gas such as described consisting primarily of methane in which proportionately less amounts of synthesis gas,

2

either carbon monoxide or hydrogen gas will be required per mole of methane produced.

A further important object of the invention is to provide a method of producing a gas sufficiently rich in methane as to be of pipeline quality in which method the production of hydrogen and methane formation reaction steps may be caused to take place at temperatures so related to each other as to permit the exothermic heat of one reaction to supply a substantial portion of the endothermic heat required for the other reaction.

A further important object of the invention is to provide a method of producing a gas sufficiently rich in methane as to be of pipeline gas quality which method will not be appreciably affected by the presence of sulphur.

A further and important object of the invention is to provide a method of producing such a methane rich gas of pipeline gas quality in which method the unreacted synthesis gas of the product from the methane forming step which is of low heating value may be advantageously returned to the system so as not to lower the quality of the gas supplied to the pipeline or reduce the efficiency of the system.

A further important object of the invention is to provide a method of producing such a methane rich gas of pipeline quality without necessity of having to go to complete conversion of the synthesis gas into methane.

A further important object of the invention is to provide a system or method of producing such a methane rich gas of pipeline gas quality in which system or method the exothermic heat given off by one reaction and the endothermic heat required for the other reaction may be so balanced as to require only a relatively small amount of tonnage oxygen in the system.

In accomplishing the above objects, it is proposed to produce methane by the reaction of hydrogen gas with carbonaceous solid fuel such as coal according to the following formula:

However, in the hydrogenation of coal, the methane content of the product gas cannot exceed the equilibrium conditions between hydrogen and methane, assuming an excess of carbon is present. For instance, the equilibrium conditions between hydrogen and methane in a system as proposed herein, would result in a maximum concentration of 10% CH₄ and 90% H₂ at 1520° F. with a reactor pressure of about 3.2 atmospheres. At 20 atmospheres, the concentration would be approximately 33% methane and 67% hydrogen, and at 54 atmospheres, the ratio would be 50% methane and 50% hydrogen. At 100 atmospheres, the concentration would be approximately 62% methane and 38% hydrogen. Thus, it is apparent that to obtain a product gas of essentially pure methane would require extremely high pressures which generally would not be desirable in actual practice. Further, to obtain methane concentrations equivalent to the equilibrium conditions, requires a long-time contact between the hydrogen and the coal. It is therefore an important object of this invention to

provide a method of hydrogenation of coal that will permit operation at generally accepted operating pressures in the general range of 40 atmospheres and at temperatures high enough that the exothermic heat of this reaction can be made useful for the production of hydrogen used in the process and effectively reuse the unreacted hydrogen in the system.

A further object of the invention is to provide a method or system of producing methane gas in which carbon may be hydrogenated to methane utilizing hydrogen in excess of that to maintain equilibrium between methane, carbon, and hydrogen in the product gas, the excess

hydrogen being kept in the system and the hydrogen consumed being formed by a reaction between steam and more carbon. According to the herein described process, these reactions may be caused to take place in the same or separate vessels but in either arrangement, the two reactions are so thermally related that all but a relatively small proportion of the endothermic heat required for one reaction is supplied by the exothermic heat of the other reaction.

A further object of the invention is to provide means and method of producing methane in which carbonaceous solid fuel is circulated between two zones, in one of which zones hydrogen is introduced in excess of that required to maintain equilibrium between the methane formed and the hydrogen at the operating temperature and pressure and in the other of which zones water in the form of steam is introduced to react with the carbonaceous solid fuel to produce hydrogen in sufficient quantity to replace that being consumed in the first zone, the methane and excess hydrogen being removed from the first zone, the methane separated from the excess hydrogen, and the excess hydrogen returned to the first zone, the hydrogen produced in the second zone being added to the first zone to maintain the required ratio of hydrogen to carbon in said zone.

A further object of the invention is to provide a system embodying means and method of producing methane in which carbonaceous solid fuel is alternately reacted with steam to form hydrogen and then with hydrogen to form methane, hydrogen being present in proportions in excess of that required for equilibrium conditions between the methane formed and the hydrogen at the operating conditions, and substantially only methane being removed whereby the reaction of carbonaceous solid fuel with steam need only be sufficient to replace the hydrogen being consumed in the forming of methane.

A further object of the invention is to provide a method or system of producing methane gas in which carbon may be hydrogenated to methane utilizing hydrogen in excess of that to maintain equilibrium between the methane and hydrogen in the product gas, approximately half of the methane produced being converted to hydrogen to supply the system with the amount of hydrogen consumed in the process to produce methane and the balance being separated from the hydrogen and made available for distribution use.

A further object of the invention is to provide a method of producing methane in which carbonaceous solid fuel such as coal may be fed to one vessel and water in the form of steam to a second vessel, the coal being reacted with hydrogen in the first vessel to produce methane and a portion of the methane being diverted to the second vessel to react with the steam to supply the hydrogen consumed in the hydrogenation step, the amount of hydrogen present in the first vessel exceeding that consumed in the hydrogenation step by an amount sufficient to maintain a desired approach to equilibrium in the system between methane and hydrogen at the operating temperature and pressures, and the excess hydrogen in the outlet gas being continuously returned with the newly manufactured hydrogen to the first vessel to maintain the system under the operating conditions required.

Many other objects and advantages of the invention will appear from the description of the invention which follows particularly when taken with the accompanying drawings in which:

FIGURE 1 represents in diagrammatic form the steps in a preferred process for producing methane gas of pipeline quality; while

FIGURES 2, 3 and 4 illustrate in diagrammatic form alternative systems for producing such a gas;

FIGURE 5 illustrates in diagrammatic form an alternative arrangement wherein the system is adapted for utilizing caking coals as the source of carbon; and

FIGURES 6, 7 and 8 illustrates in diagrammatic form further embodiments of a system according to the pres-

ent invention in which the hydrogen being consumed to form methane is produced by a reaction of steam with carbon.

According to the present invention it is proposed to form methane by hydrogenating carbon under controlled temperature and pressure with or without benefit of a catalyst. The reaction can be illustrated by the previously mentioned general formula:

and for the preferred embodiment of the invention is carried on at temperatures in the general range of 1500° F. to 1700° F. and at approximately 40 atmospheres pressure or 600 p.s.i.a. This is also within a range of temperatures that can be made useful for the production of hydrogen.

Since the reaction of hydrogen with carbon to form methane, however, does not go to completion at the above mentioned temperatures and pressures, that is, equilibrium conditions are not such that all of the hydrogen gas present in the reaction zone will react with the carbon, an excess amount of hydrogen is provided. When the reaction is carried out at the above mentioned temperature and pressure, preferably the amount of hydrogen gas is increased so that about four moles of H_2 are initially present for each mole of C being consumed per mole of methane produced. By this means the reaction of one carbon mole with two hydrogen moles may be maintained at the desired reaction temperature of about 1500° F. and 40 atmospheres pressure leaving two moles of unreacted hydrogen. The reaction would be substantially as follows:

The methane (CH_4) may be separated from the hydrogen by conventional means such as a fractionator using the so-called low temperature process and made available to the supply line or other collecting station. Other conventional separating means or processes might also be used to remove the methane. If desired the separating process may be designed to permit storage of the methane in liquid form on an adsorbant or as a hydrate following known practice. The two moles of unreacted hydrogen (H_2) are then returned to continue hydrogenation of carbon as it is fed to the reaction zone to produce more methane. Two moles of hydrogen gas are consumed in the system to produce one mole of methane which compares with the previously discussed prior art processes in which four moles of synthesis gas are required to produce one mole of methane.

The hydrogen gas which is used up in the process and must be replaced to maintain the process can be obtained by using any of the commonly known systems for producing synthesis gas. However, a preferred method of obtaining hydrogen for use in this process is to reform a part of the methane produced into H_2 by the reaction—

or

Approximately one-half of the methane produced is made immediately available for pipeline use while the other half is held in the system for reforming to replace the hydrogen consumed in the hydrogenation step. This reforming step can be carried out at temperatures which are below the temperature of the hydrogenation reaction or methane forming step, and therefore, the exothermic heat of hydrogenation can be used to supply a substantial portion of the endothermic heat required in the methane reduction. Although the reaction is preferably carried out at 1300° F. and 40 atmospheres pressure, the temperature may be varied between 1200° F. and 1700° F. and the pressure between 20 and 50 atmospheres or higher dependent upon the engineering requirements for the specific application.

The complete reaction from the carbon to methane thus becomes:

Roughly 3000 B.t.u.'s are required to keep the system going, not counting losses. This would be at the rate of approximately 6000 B.t.u. of reaction heat per mole of methane made available at the collecting station, which compares with the approximately 100,000 B.t.u. theoretical reaction heat per mole of methane produced which was required by some of the prior art methods of producing methane.

The process as thus generally described can take several specific forms, and can best be described by assuming a hypothetical non-caking coal, with no volatiles, that can be considered as carbon and reacting according to the equations previously given. Referring to FIGURE 1 of the drawing, 10 represents the hydrogenation vessel or chamber to which the coal is fed from hopper 11 through line 12. 13 represents a series of coils which may be of a character such as is found in a vertical water tube boiler and comprise the methane reduction area. In these coils is located nickel or other catalyst for the methane reduction part of the process. The reverse arrangement might also be used wherein the carbon is fed to the coils and the methane reduction takes place in the surrounding vessel. Since the carbon is in fluidized form the rate of heat transferred through the coils 13 should be high and result in an efficient and effective system.

Four moles of hydrogen from line 24 and one mole of carbon from hopper 11 are fed through line 12 into the hydrogenation vessel 10 to replace each mole of carbon being consumed in the hydrogenation process. Ash and unreacted carbon mixed therewith will be removed from vessel 10 through 10a for economical operation of the process. The hydrogenation process is preferably caused to take place at approximately 1500° F. although the temperature may be as high as 1700° F. Only two moles of hydrogen are required per mole of carbon consumed to form one mole of methane. Consequently, for each mole of carbon consumed in vessel 10 there is available a gas comprising one mole of methane and two moles of unreacted hydrogen. This gas mixture is directed under 40 atmospheres' pressure through pipe 14, then at desired conventional pressures through the heat exchanger 15, through separator 17 where any tar and the like is removed and then into fractionator 18.

Fractionator 18 is of conventional construction, operating on the principle that methane and hydrogen as well as other impurities contained in the gas mixture will condense at different temperatures and so may be readily separated. Pressures as well as temperature may be varied to effect the separation. The condensing step is not carried to completion, since approximately half of the methane needs to be retained in the system to provide on reduction the two moles of hydrogen consumed in the hydrogenation vessel 10. Thus, .5 mole of methane is collected at outlet 18a, while the other .5 mole of methane and two moles of unreacted hydrogen are passed through line 19, through the heat exchanger 15 where the gas is reheated to 1200° F., and through line 20 into methane reduction coils 13. Impurities such as sulphur in the gas entering fractionator 18 are preferably collected at 18b so as not to be recirculated through the system. It is also to be understood that although the pressure of the gas as well as its temperature is reduced from the system's normal pressure of 40 atmospheres in the fractionator 18 for the purposes of the condensation and separation steps therein taken, this pressure is re-established in line 19 by suitable means, such as a pump (not shown). It is also understood that any

other known means for removing impurities might be substituted for the above.

One mole of water in the form of steam enters the system through line 20 for reaction with each 0.5 mole of methane in the reduction coil 13 to produce two moles of hydrogen, and 0.5 mole of carbon dioxide. Actually a somewhat larger proportion of steam should be added to insure complete reduction of the methane. The excess H_2O will be removed with the carbon dioxide at 23. As mentioned previously, a slight imbalance exists between the amount of exothermic heat given off in the hydrogenation of the coal and the endothermic heat required for the methane reduction step. This additional heat can be supplied by burning a small amount of the methane in the coils 13 with a small amount of relatively pure oxygen added at 21, with a corresponding reduction in the CH_4 available at 18a. Although the oxygen could be added in line 20 with the steam, it is preferred that the oxygen be added as close to the coils 13 as possible, so as to confine the burning to the area where the heat requirement exists rather than in line 20. Conceivably, a small amount of hydro-carbon fuel, such as butane, might be supplied with the oxygen. This would avoid the requirement of burning a portion of the methane to supply the additional amount of heat required. The products of the combustion plus the 2 moles of hydrogen and 0.5 mole of carbon dioxide formed by the reduction of the methane exit from coils 13 through line 22 to the separator 23 where any undesired products of combustion, carbon dioxide and any water present are removed. This leaves in line 24 the two moles of hydrogen formed by the methane reduction reaction in the coil 13 plus the two moles of unreacted hydrogen which were not consumed in the hydrogenator 10 and have been passed through the system and thus four moles of hydrogen are available to be fed into line 12 to continue the process. Preferably, a super-heater 25 is provided in line 24 to bring the hydrogen gas to the desired temperature.

Although the above system or arrangement is preferred because sulphur from the coal will have been removed and collected at 18b or otherwise before the gas reaches the methane reduction coil, alternatively, if a sulphur resistant catalyst is available for use in the methane reduction zone or sulphur is not presented in the carbon supply then the methane reduction can immediately follow hydrogenation and precede the fractionating step. Such an alternative arrangement is illustrated in FIGURE 2 of the drawing. In this instance, one mole of carbon in the form of coal is fed from hopper 111 and with four moles of hydrogen from line 124 is fed through line 112 into the hydrogenation vessel 110 where the reaction produces one mole of methane, and two moles of hydrogen gas pass through unreacted, as in the previously described system. However as distinguished from the prior system, in this modification, the hydrogen-methane mixture is directly passed via lines 114 and 120 to the methane reduction coils 113 and then to the fractionator 118 through line 122 after passing through heat exchanger 115 and tar remover 117. As previously, the required amounts of steam, tonnage oxygen and fuel are added through 120 and 121 respectively. In this instance, the methane reduction is carried only half way through completion in the coils 113, that is, only sufficiently to reduce the part of the methane necessary to produce the two moles of hydrogen which replace the two moles of hydrogen consumed in the hydrogenation vessel 110. Therefore, in this modification, there will be four moles of hydrogen gas plus a half mole of carbon dioxide and a half mole of non-reduced methane gas passing to the fractionator 118 through line 112. On separation, the half mole of methane exits to the collecting station through line 118a while the carbon dioxide as well as the non-used steam and tonnage oxygen and other impurities are removed through 118b or in any

desired manner. The remaining four moles of hydrogen gas are withdrawn through line 124 into line 112 so as to be redirected into the hydrogenation vessel 110 after being reheated in heat exchanger 115 and are available to react with more carbon.

FIGURE 3 illustrates a still further possible modification. In this instance, carbon in the form of coal is supplied from hopper 211, mixed with hydrogen in line 212 and directed to the hydrogenation vessel 210. The hydrogen and carbon there react to produce one mole of methane which with the two moles of non-reacted hydrogen pass through line 214 as before. The path of the gas, however, in this modification is divided so that only one half of the gas is directed through line 214a, through heat exchanger 215, through tar separator 217 to the fractionator 218 while the other half is directed through line 214b directly to line 219 and into the methane reduction coils 213. Preferably a separator 226 would be provided in line 214b to remove tar and other impurities, including sulphur. The half mole of methane sent to the fractionator 218 is separated from the mole of non-reacted hydrogen and made available for pipeline use through 218a, impurities being removed at 218b. The remaining mole of non-reacted hydrogen leaves the fractionator through line 219 and is reunited at the juncture of line 214b and 219 with the other mole of non-reacted hydrogen and half mole of methane being fed to the methane reduction coil 213. The latter half mole of methane is reduced in said coils 213 to hydrogen by means of steam added at 220 and tonnage oxygen at 221. Thus, as in the prior arrangements, there will be four moles of hydrogen gas exiting from the reduction coils 213, which are directed through line 222, and after being separated from the carbon dioxide, etc., by separator 223, are reheated at 225 and passed into line 212 to continue the process. It will be understood that in this modification the dividing of the gas product between lines 214a and 214b can be controlled by suitable valve means or the like, and so that only the portion of methane required to be reduced to hydrogen will pass through line 214b, 40 permitting all the methane passed to the fractionator 218 to be collected at 218a.

There may be instances when it is desirable to use natural gas, propane, butane or the like as the substance for producing the hydrogen to replace that consumed in the hydrogenation vessel. FIGURE 4 illustrates a system by means of which such a substance may be utilized. In this case, coal is supplied from hopper 311 to line 312, as before, where it is mixed with hydrogen gas directed into the hydrogenation vessel 310. After completion of the reaction, the one mole of methane and two moles of non-reacted hydrogen per mole of carbon consumed are directed through line 314, through heat exchange 315 to separator 317 which removes the tar and then to the fractionator 318. In this instance, all of the methane produced is separated from the non-reacted hydrogen and made available for pipeline use through lead 318a, impurities being removed through 318b as in the previous systems. The two moles of non-reacted hydrogen gas are then directed through line 319 back to the entering line 312. Natural gas or some suitable substance as mentioned previously is directed through line 327 into the methane reduction coils 313 after being heated in heat exchanger 315. Steam is supplied through line 320 and tonnage oxygen through 321 as before. Upon completion of the reaction two moles of hydrogen and half mole of carbon dioxide exit from the coils 313 through line 322. The carbon dioxide is separated out at 323 and the two newly formed moles of hydrogen gas are added through line 324 to the two moles of the non-reacted hydrogen in line 319 to make the required four moles of hydrogen available in line 312 to mix with the coal from the hopper 311 to continue the process of hydrogenation in the vessel 310.

It may be desirable, such as during peak loads, to re-

form a higher molecular weight hydrocarbon such as butane, propane, gasoline, or the like, instead of methane. This could be accomplished in the apparatus just described with reference to FIGURE 4 with only minor changes, as would be well known to those skilled in the art, and so providing a system capable of supplying twice its normal capacity for peak load purposes.

The above discussion, for ease of understanding, has been predicated on an assumption that the carbonaceous solid fuel was substantially pure carbon. However, the ordinary coal contains volatiles which when heated result in gases such as hydrogen, carbon monoxide and methane and other hydrocarbons in addition to tars, the major portions of which are driven off at the operating temperature of 1500° F. and may be used to further increase the yield. Accordingly, reference to hydrogen will be understood to mean a synthesis gas stream which is predominantly hydrogen.

If a caking coal is to be gasified, its caking properties can be destroyed by a conventional carbonization process, such as is well known to those skilled in the art, at temperatures between 900° F. and 1500° F. and the combustible portion of the product gas introduced into the system ahead of the fractionator and the resulting char, which is non-caking, introduced into the hydrogenation vessel 10, 110, 210 or 310 as found in any one of the previously discussed systems. Alternatively, the gas products could be fractionated separately and the separated products used in the system. The char above referred to which remains after carbonization will consist primarily of carbon although some residual amounts of volatiles as well as ash may remain. Nevertheless, whenever in the discussion and claims the term carbon is used, it is to be understood as including such a char containing residual volatiles and ash as well as coal.

A preferred method of destroying the caking properties of a caking coal would be by an arrangement such as is illustrated in FIGURE 5 wherein coal in fluidized form is heated in vessel 410 to 1500° F., which is sufficient to drive off the volatiles, and is kept in motion by forced circulation through lines 428, 412 and 430 at a rate some ten to thirty times the rate at which fresh coal is fed from hopper 411. Ash is removed at 429 and the required amount of hydrogen for the hydrogenation process is introduced into the circulating system from line 424.

As an example of how the volatiles given off by coal may be advantageously used for their enrichening effect, if 1.05 tons are fed into vessel 410 from hopper 411, and heated through 1500° F. the volatiles which are driven off and pass into the system through line 414 have been found to comprise roughly 13 moles of hydrogen, 5.5 moles of carbon monoxide and hydrocarbon which can be considered as the equivalent of 16 moles of methane in addition to 97 pounds of tar, leaving 72 moles of residual carbon, about 7 moles of which will be lost in the ash and exit through 429. About 260 moles of hydrogen needs to be supplied to line 430 through line 424 to combine with the remaining 65 moles of carbon in vessel 410 to provide the desired ratio of 4 moles of hydrogen for each mole of methane produced. The resulting gas product of the reaction will be a mixture comprising roughly 65 moles methane and 130 moles of non-reacted hydrogen gas in addition to the 16 moles of methane, 5.5 moles of carbon monoxide and 13 moles hydrogen constituting the volatiles driven off the coal. This mixture of volatiles and gas produced from the reaction is directed under 40 atmospheres' pressure through pipe 414, through the heat exchanger 415 to separation vessel 417 where the tar and other impurities are removed and finally to the fractionator 418.

In the arrangement illustrated in FIGURE 5 the separating step will not be carried to completion, since some portion of the methane needs to be retained in the system to provide on reduction the two moles of hydrogen

consumed in the hydrogenation step. In this case, 33 moles are required leaving 32 of the 65 moles of methane produced in the hydrogenation step available for collection at 418a. The 16 moles of methane and 5.5 moles of carbon monoxide comprising the volatiles may be also collected, making a total of 48 moles methane and 5.5 moles carbon monoxide constituting the product gas.

The remaining 33 moles of methane and 130 moles of non-reacted hydrogen are then withdrawn from the fractionator through pipeline 419, through the heat exchanger 415 so as to be reheated to 1300° F., and to the methane reduction coils 413.

An excess of 60 moles of water in the form of steam enters the system at 420, and is reacted with the 33 moles of methane in the reduction coils 413 in the presence of the catalyst to produce 120 moles of hydrogen. As previously mentioned, a slight imbalance exists between the amount of exothermic heat given off by the hydrogenation of the coal and the endothermic heat required in the methane reduction step. There are also supply losses for which compensation must be made. The additional heat requirement can be satisfied, in the present example, by burning about 3 moles of the methane with tonnage oxygen provided at 421. Thus the following appropriate reactions will be considered to take place in the methane reduction coils 13:

Although a small amount of methane is thus consumed in the process to provide the additional amount of endothermic heat required for reaction a, the 120 moles of hydrogen produced from the 30 moles of CH_4 in Equation a will when added to the 130 moles of hydrogen which was not reacted during hydrogenation of the coal plus the 13 moles obtained as a part of the volatiles in the carbonization step, make available a total of 263 moles of hydrogen which is more than enough to provide the required 4 to 1 ratio of hydrogen to carbon consumed to produce 1 methane. The carbon dioxide and water produced are removed from the system at 423 and the 263 moles of hydrogen continued along lines 424 and 430 to vessel 410.

Although the system as thus discussed more closely resembles that discussed with reference to FIGURE 1, it should be understood that this was merely for convenience sake, and substantially the same results would be obtained if the system were modified along the lines illustrated by FIGURES 2, 3 and 4. In each instance, the equivalent of two moles of non-reacted hydrogen per mole of carbon consumed in the vessel 410 for hydrogenation are passing constantly through the system while two moles of hydrogen gas are being formed in the methane reduction coil to replace the two moles of hydrogen gas being consumed in the hydrogenation part of the process to form said half mole of methane. Steam and coal are the only raw materials supplied outside of the relatively small amount of tonnage oxygen added to balance the endothermic heat of the methane reduction with the exothermic heat of hydrogenation.

The volatiles of ordinary coal will constitute about 20 to 30 percent of the heat of the coal in the form of gaseous products including methane as well as hydrogen and carbon monoxide and, as illustrated in the example, permit minor change in the mentioned mole ratios. Not only is the hydrogen portion of said volatiles available for hydrogenation purposes, but its carbon monoxide content might also be converted to hydrogen rather than collected as a part of the product gas. This could be accomplished by means of a well known water gas shifting means provided in line 422 at 431 and connected to the steam source by line 432. Because of the additional amounts of hydrogen obtained from the volatiles, actually only about 0.45 of a mole of methane

would need to be converted into hydrogen. The overall reactions would be approximately—

Thus the system is theoretically substantially thermo-neutral. However, there are various losses in the system for which additional amounts of heat will have to be supplied. These would include the super-heater 425, the generation of steam to be supplied at 420, etc.

Analyzing the system, it will be seen that as a result of the several steps of de-volatilization, hydrogenation, reforming and combustion that: 1.05 tons of coal (72C+volatiles) + 60 H_2O + 6 O_2 yielded as pipe line gas 48 CH_4 + 5.5 CO , and as by-products

lbs. tar.

20 By estimation, the system power requirements for gas compression, tonnage oxygen production and auxiliaries would amount to 45.5 therms. If a credit of 35.8 therms were given for tar, carbon in the ash and waste heat available other than transferred within the system, then the net additional heat required to maintain the system would be about 9.7 therms per mole of methane produced. This, when added to the 1.05 tons of coal calculated at 235 therms per ton, would give a total input into the system of roughly 256.7 therms.

30 Then considering the pipeline gas collected to be the equivalent of 49.5 CH_4 (giving 1.5 credit to the 5.5 CO collected) at 3.83 therms per unit of CH_4 , 190 therms would have been obtained so that the overall system thermal efficiency would be 190/256.5 or 74%.

35 In the systems described previously, the two moles of hydrogen consumed in the hydrogenation vessel are produced by reforming or reducing a portion of the methane product except in the system according to FIGURE 4, which uses an external source for supplying the methane to be reduced to hydrogen. An alternative method of gasification according to the present invention would be by a system as illustrated in FIGURE 6, wherein hydrogen is formed by the reaction of carbon with steam. The arrangement is adapted for use with either caking

40 or non-caking coals and comprises a gasification vessel 513 which is heated to 1200° F. and a hydrogenation vessel 510 which is preferably heated, as in the prior systems, to 1500° F. to effect hydrogenation of the carbon to methane. As will be seen in FIGURE 6, fluidized

45 coal or other carbonaceous fuel is continuously circulated between the hydrogenation vessel 510, and the gasification vessel 513 via connecting lines 531 and 532, fresh fuel being added from hopper 512 into line 531 to replace the portion being consumed in vessel 510 by reaction with

50 hydrogen supplied via line 519 and the portion being consumed in vessel 513 by reaction with steam entering via line 520 to form hydrogen. Because the fuel circulates between both vessels, the catalyst that is used for

55 the reaction in vessel 513 must also be compatible with the hydrogenation reaction in vessel 510. One such catalyst is sodium carbonate. This catalyst is not only effective for the gasification reaction, but will also help to increase the formation of methane in the hydrogenation reaction.

60 By means of the described movement of fuel between the two vessels 510 and 513, the exothermic heat of the hydrogenation reaction can be used to furnish the endothermic heat required for the gasification reaction. The two reactions are illustrated by the following formulas:

Adding the formulas together, obtains the following:

Losses in the system have been calculated to amount to about 36,500 B.t.u. per mole of methane produced. This added to the 6,500 B.t.u. of addition heat required for the gasification reaction in vessel 513 makes a total of 42,500 B.t.u. This may be obtained by supplying a .25 mole of oxygen through line 520 in addition to the two moles of water in the form of steam. This will be used to burn an additional .25 mole of carbon to provide the desired additional units of heat. The two moles of hydrogen and one mole of carbon dioxide exit from the hydrogen producing vessel 513 through line 522. The carbon dioxide is removed at 523 and the two moles of hydrogen continued to line 519 where they combine with the two moles of unreacted hydrogen from the fractionator 518 and are heated in heater 525 and thence fed into the hydrogenator 510. As in the previously discussed systems, according to FIGURES 1 through 5, the gas exiting from the hydrogenation vessel 510 comprises one mole of methane and two moles of unreacted hydrogen for each mole of carbon consumed therein, plus volatiles, and is passed via line 514 through the heat exchanger 515 to the separator 517 where tar is removed, and thence to the fractionator 518. The methane is removed for collection through line 518a and the remaining two moles of unreacted hydrogen returned to the hydrogenation vessel 510 after being reheated in heat exchanger 515.

In analyzing the system, it has been found that 94,200 B.t.u. will be consumed in preheating the reactants and producing oxygen and compression, from which 40,200 B.t.u. may be subtracted for available waste heat, making the net requirements of the process 54,000 B.t.u. or the equivalent of .32 carbon mole. This added to the 2.25C consumed in the reactions to produce a mole of methane, gives a total of 2.57C or 4.36 therms as the net input of the system. .75 therms are added to this figure for auxiliaries making the gross fuel requirements per mole of methane amount to 5.11 therms. Considering that the output of the system is one mole of methane or 3.83 therms, then the overall efficiency will be

$$\frac{3.83}{5.11} \text{ or } 75\%$$

Since both reactions involve coal or other carbonaceous solid fuel and utilize sodium carbonate as a common catalyst, conceivably the two reactions might take place in the same vessel or chamber. Such an arrangement is illustrated by FIGURE 7. In this system, coal is supplied from hopper 612 through line 611 and line 633 to a vessel 610. Water in the form of steam, and tonnage oxygen for combustion purposes, is fed through line 620, valve 635, line 634 and line 633 into said vessel 610 while hydrogen is supplied to the vessel 610 through line 619, valve 636, and lines 634 and 633. Valves 636 and 635, respectively, may be operated so that during one alternate period of time, hydrogen will be fed into vessel 610 to react with the carbon fuel to produce methane and, in a second alternate period so that water in the form of steam will be supplied to the vessel 610 to produce hydrogen to replace that consumed during the first mentioned period. Thus the following two reactions will alternately take place in said vessel 610:

- (1) $C + 2H_2O \rightarrow 2H_2 + CO_2 - 39,000 \text{ B.t.u.}$
- (2) $C + 4H_2 \rightarrow CH_4 + 2H_2 + 32,570 \text{ B.t.u.}$

Both the two moles of hydrogen produced in Reaction 1 and the one mole of methane and two remaining moles of unreacted hydrogen of Reaction 2 will of course exit as the product gas of vessel 610 through line 614 but as in the previous systems line 614 will lead to a fractionator or separator where the mole of methane is collected and the four moles of hydrogen returned to line 619 to be fed into vessel 610 during the hydrogenation period. Also, if desired the products of the two reactions might be collected separately.

The reaction of carbon with the hydrogen is exothermic and continues until the temperature of the carbon reaches approximately 1700° F. while the reaction of the carbon with steam to produce the hydrogen consumed is endothermic and lowers the temperature from 1700° F. to 1500° F. so that the process may be considered as continuous and in balance except for the additional 6,500 B.t.u. of endothermic heat required in Reaction 2. This, however, can be supplied by adding tonnage oxygen with the steam and used to burn carbon as in the arrangement according to FIGURE 6.

As a further modification, the steam and hydrogen may be mixed in related proportions, so that the reaction of carbon with the hydrogen to produce methane and the reaction of carbon with steam to produce hydrogen may take place simultaneously in said vessel 610. Tonnage oxygen will also be supplied to burn a portion of the carbon as in the previous systems.

As a further alternative, two vessels may be utilized as in the arrangement according to FIGURE 8. In this system carbonaceous solid fuel is supplied from hopper 712 through suitable lead lines 711 and 733 to vessel 710 and through leads 711a and 733a to vessel 710a. Steam is supplied to vessel 710 via line 720, valve 735, and lines 734 and 733 and to vessel 710a from line 720 via valve 735a, lines 734a and 733a. Hydrogen is also supplied to each vessel from line 719 passing to vessel 710 via valve 736 and line 733 and to vessel 710a via valve 736a and line 733a. Thus the valves may be operated so that while hydrogen is being fed to vessel 710, tonnage oxygen and steam is fed to vessel 710a and then in the reverse. Thus while hydrogenation of carbon to methane is taking place in one vessel, hydrogen is being newly formed in the other vessel so that there will be a substantially uniform rate of removal of methane from the fractionator.

If desired, the coal may be fed to the respective vessels only during the hydrogenation part of the process, the coal remaining in the vessel then being used for the reaction of steam to form hydrogen. In this way fresh coal is always available for the reaction with hydrogen. Also there is no problem of providing additional heat to compensate for the cooling-off effect of the added coal in the hydrogen forming step.

Obviously, many further modifications and variations of the invention as hereinbefore set forth may be made without departing from the spirit and scope thereof, and it is to be understood that the above description is not to be taken in a limiting sense, but only as illustrative of my invention. For that reason, only such limitations should be imposed as are indicated in the appended claims.

Having described my invention, I claim:

1. In a process of manufacturing pipeline quality gas, the steps comprising arranging two reaction zones in direct heat transfer relation; reacting hydrogen with carbonaceous solid fuel in one zone in the presence of an excess amount of hydrogen to produce methane at a temperature and pressure which produces a product gas consisting essentially of methane and hydrogen; reacting methane with steam in the other reaction zone, at a temperature below the temperature in said one zone, to produce hydrogen in sufficient quantity to replace the hydrogen being consumed in the first zone; the available exothermic heat from the first reaction zone being utilized to supply to said other reaction zone at least a substantial part of the endothermic heat required to produce hydrogen; separating out at least a portion of substantially only the methane which is produced in the first zone, collecting the same and returning the excess hydrogen to the first zone for re-use in the process, together with the hydrogen produced in said other zone.

2. In a process of manufacturing pipeline quality gas, the steps comprising maintaining two reaction zones in direct heat transfer relation, feeding volatiles-containing carbonaceous solid fuel and hydrogen to a first zone,

driving off volatiles including hydrogen, carbon monoxide and methane while reacting the hydrogen with the residual carbonaceous material at a temperature in the range from approximately 1500° F. to 1700° F., and at a pressure in excess of approximately 40 atmospheres to form a product gas consisting essentially of methane and unreacted hydrogen; separating out a portion consisting essentially of methane; returning the unreacted hydrogen to said first zone; in the second zone, at a temperature above approximately 1200° F. but below the temperature in said first zone, reducing a portion of the unseparated methane to produce a sufficient amount of hydrogen to replace the hydrogen consumed in the first zone; utilizing the available exothermic heat of the reaction in the first zone to supply to said second zone at least a substantial part of the endothermic heat required to produce hydrogen therein; and returning the newly produced hydrogen to said first zone.

3. In a process of manufacturing a pipeline quality gas, the steps comprising maintaining two reaction zones in direct heat transfer relation, feeding carbonaceous solid fuel to one reaction zone; there reacting hydrogen with the carbonaceous solid fuel to form methane in the presence of an excess amount of hydrogen at a pressure and at a temperature in the range from approximately 1500° F. to 1700° F. which produces a product gas consisting essentially of methane and unreacted hydrogen; removing the product gas from said reaction zone and feeding it to the second zone; supplying steam to said second zone to reduce a part of the methane to hydrogen while utilizing the available exothermic heat of the reaction in the first zone to supply at least the greater portion of the endothermic heat requirement of the methane reduction step conducted in said second zone, a sufficient proportion of said methane being reduced to hydrogen in said second zone to replace that consumed in the first zone; then separating out the remainder of the methane from the product gas, collecting said separated out methane remainder and returning the unreacted and newly formed hydrogen to the first reaction zone to continue the process.

4. In a process of manufacturing pipeline quality gas, the steps comprising maintaining two reaction zones in direct heat transfer relation, feeding carbonaceous solid fuel to one zone; reacting hydrogen with the carbonaceous solid fuel in said zone at a pressure and at a temperature in the range from approximately 1500° F. to 1700° F. to form methane in the presence of an excess amount of hydrogen which produces a product gas consisting essentially of methane and unreacted hydrogen; removing a portion of the product gas embodying a mixture of unreacted hydrogen and methane to a second zone; utilizing the available exothermic heat of the reaction in the first zone to supply at least the greater portion of the endothermic heat required in said second zone and reducing said methane in said second zone to hydrogen at a temperature below the temperature in said first zone, the portion of the product gas removed to said second zone being sufficient that the hydrogen resulting from the reduction of the methane of said portion will equal that being consumed in the first zone; separating out the methane from the remaining portion of the product gas and returning the unreacted hydrogen of both portions of the product gas and the newly formed hydrogen to the first zone.

5. In a process of manufacturing pipeline quality gas, the steps comprising maintaining two reaction zones in direct heat transfer relation, feeding carbonaceous solid fuel into one zone, there reacting said carbonaceous solid fuel with hydrogen at a pressure and at a temperature in the range from approximately 1500° F. to 1700° F. to form methane, more hydrogen being present in said zone than is reacted, which produces a product gas consisting essentially of methane and unreacted hydrogen; removing the product gas from said first zone; separating out the methane as the desired product, and returning substantially all the unreacted hydrogen to the first zone; reacting

hydrocarbon with steam in said second zone at a temperature below that in said first zone to form hydrogen and other products, utilizing the available exothermic heat in the first zone to supply a substantial portion of the endothermic heat required in said second zone, the hydrogen so formed being used to replace that consumed in the first zone.

6. In a process for the manufacture of pipeline quality gas from carbonaceous solid fuel by the reaction of carbon with hydrogen to produce methane, the improvement which comprises, in a first reaction, reacting hydrogen with carbonaceous solid fuel in the presence of an excess amount of hydrogen to produce methane at a temperature and pressure which produces a gaseous product consisting essentially of methane and unreacted hydrogen, said reaction being exothermic; separating out from said gaseous product a part comprising pipeline quality gas consisting essentially of methane, and collecting said part for pipeline gas use; returning essentially all the unreacted hydrogen to said reaction; in a second reaction, reacting steam with an ingredient selected from the group consisting of carbonaceous solid fuel and hydrocarbon to produce additional hydrogen in amounts sufficient to maintain the process in operation, said second reaction being endothermic, so controlling the pressure and temperatures at which the two reactions are caused to take place that only a slight imbalance exists between the amount of exothermic heat given off in the first reaction and the greater endothermic heat requirements of the second reaction, the two reactions being conducted at a temperature gradient which permits a transfer of heat from the exothermic first reaction to the endothermic second reaction, and continuously maintaining the heated solids of the first reaction in direct heat transfer relation with the zone in which the second reaction takes place so that said exothermic heat of said first reaction is used to supply all but a relatively small proportion of the endothermic requirements of the second reaction.

7. In a process according to claim 6 wherein carbonaceous solid fuel is reacted with steam in a gasification zone at a temperature between 1200 and 1700° F. and pressure sufficient to effect therein a useful steam conversion to hydrogen, wherein carbonaceous solid fuel is concurrently reacted with preheated hydrogen in a hydrogenation zone at a higher temperature in the range 1500 to 1700° F. and at the same pressure, wherein said hydrogenation zone is maintained at an average temperature above that of said gasification zone, and wherein a direct transfer of heat is established between the two zones by continually transferring carbonaceous solid fuel from said hydrogenation zone to said gasification zone while transferring carbonaceous solid fuel from said gasification zone to said hydrogenation zone, wherein gaseous reaction products are recovered from said zones, wherein gaseous reaction products are recovered from said zones, wherein substantially all carbon dioxide and other undesired impurities are removed therefrom, wherein there is recovered from the residue of said gaseous reaction products a high B.t.u.-content product gas of pipeline quality consisting essentially of methane, and the remainder of said gaseous reaction products is recycled as substantially pure hydrogen gas at an elevated temperature to said hydrogenation zone.

8. In a process according to claim 6 wherein steam is passed upwardly through a gasification zone containing finely divided reactive carbonaceous solid fuel maintained at a pressure near 40 atmospheres and a temperature sufficient under fluidized reacting conditions to effect therein a useful steam conversion to hydrogen, wherein preheated hydrogen gas is concurrently passed upwardly through a hydrogenation zone containing finely divided reactive carbonaceous solid fuel maintained at a pressure near 40 atmospheres and at a higher temperature in the range of 1500 to 1700° F. under fluidized reacting conditions, said

temperature in said hydrogenation zone being higher than in said gasification zone, wherein gaseous reactant products are recovered from said gasification and hydrogenation zones, and substantially all carbon dioxide and other undesired impurities are removed therefrom, wherein the residue of said gaseous reactant products is separated into a substantially pure hydrogen gas and a high B.t.u.-content product gas of pipeline quality consisting essentially of methane, wherein the high B.t.u.-content product gas is collected and said substantially pure hydrogen gas is recycled at an elevated temperature to said hydrogenation zone, and said carbonaceous solid fuel is circulated between said zones so that the carbonaceous solid fuel moving from said hydrogenation zone is hotter than carbonaceous solid fuel moving from said gasification zone.

9. In a process according to claim 6 wherein the additional hydrogen required to maintain the process in operation is obtained in the second reaction by the reaction of carbonaceous solid fuel with steam.

10. In a process according to claim 6 wherein the additional hydrogen to maintain the process in operation is obtained in the second reaction by the reaction of carbonaceous solid fuel with steam, and the balance of the endothermic requirements of said second reaction is supplied by reacting relatively pure oxygen with a portion of the carbonaceous solid fuel.

11. In a process according to claim 9 wherein the carbonaceous solid fuel used is partially reacted fuel from the first reaction.

12. In a process according to claim 10 wherein the carbonaceous solid fuel used is partially reacted fuel from the first reaction.

13. In a process according to claim 9 wherein a single catalyst is used for accelerating the two reactions.

14. In a process according to claim 9 wherein sodium carbonate catalyst is used for accelerating the two reactions.

15. In a process according to claim 9 wherein the two reactions are carried on in separate reaction zones and the two zones are so arranged as to permit transfer of the carbonaceous solid fuel from one to the other, and fresh carbonaceous solid fuel is fed into the system by mixing it with the partially reacted fuel proceeding from the second reaction zone to the first reaction zone.

16. In a process for the manufacture of pipeline quality gas from carbonaceous solid fuel by the reaction of carbon with hydrogen to produce methane, the improvement which comprises, in a first reaction, reacting hydrogen with carbonaceous solid fuel in the presence of an excess amount of hydrogen to produce methane at a temperature and pressure which produces a product gas consisting essentially of methane and unreacted hydrogen, said reaction being exothermic, removing said product gas, separating out pipeline quality gas consisting essentially of methane from said removed gas, and collecting the same as a product, returning essentially all the unreacted hydrogen to said reaction, in a second reaction, reacting steam with an ingredient selected from the group consisting of carbonaceous solid fuel and hydrocarbon to produce additional hydrogen in sufficient quantity to maintain the first reaction in operation, said second reaction being endothermic, so controlling the pressure and temperatures at which the two reactions are caused to take place that only a slight imbalance exists between the amount of the exothermic heat given off in the first reaction and the greater endothermic heat requirements of the second reaction, the two reactions being conducted at a temperature gradient which will permit a transfer of heat from the exothermic first reaction to the endothermic second reaction, maintaining the heated carbonaceous solid fuel of the first reaction in direct heat transfer relation with the zone in which the second reaction takes place so that said exothermic heat of said first reaction supplies all but a relatively small portion of the endo-

thermic requirements of the second reaction, and supplying the balance of the endothermic requirements of said second reaction by reacting relatively pure oxygen with a portion of the materials in said zone which are undergoing reaction to produce the additional hydrogen.

17. In a process for the manufacture of pipeline quality gas from a carbonaceous solid fuel by the exothermic reaction of carbon with hydrogen to produce methane, the improvement which comprises, in a first reaction, reacting hydrogen with carbonaceous solid fuel at near 40 atmospheres of pressure and at a temperature in the approximate temperature range of 1500° to 1700° F. which produces a gaseous product consisting essentially of methane and unreacted hydrogen, separating out a portion therefrom of pipeline quality gas consisting essentially of methane and collecting said portion; in a second reaction reacting steam with an ingredient selected from the group consisting of carbonaceous solid fuel and hydrocarbon at a pressure near 40 atmospheres and at a temperature in the approximate range of 1200 to 1700° F., but a temperature less than the temperature of the first reaction, which produces hydrogen in amounts sufficient to replace that being consumed in said first reaction; and maintaining the heated carbonaceous solid fuel of the first reaction in direct heat transfer relation with the zone in which the second reaction takes place so that the exothermic heat of the first reaction is transferred to the reactants of said second reaction which supplies the major portion of the endothermic heat requirements for said further reaction, and returning the unreacted hydrogen and the newly formed hydrogen to said reaction zone to continue the process.

18. In a process of manufacturing pipeline quality gas, the steps comprising simultaneously conducting two reactions in direct heat transfer relation, in one of said reactions, reacting hydrogen with carbonaceous fuel in the presence of an excess amount of hydrogen to produce methane at a temperature and pressure which produces a product gas consisting essentially of methane and hydrogen; in the other of said reactions, reacting a material selected from the group consisting of carbonaceous solid fuel and hydrocarbon with steam to produce hydrogen in sufficient quantities to replace the hydrogen being consumed in the first of said reactions, conducting the two reactions at a temperature gradient which permits a transfer of the available exothermic heat from said first reaction to the second reaction which is endothermic, the temperatures and pressures at which the two reactions are conducted being so related that the said exothermic heat of the first reaction supplies a substantial part of the endothermic heat required by the second reaction to produce hydrogen, separating out at least a portion of substantially only the methane which is produced in said first reaction, collecting the same as a product gas of pipeline quality, and returning the excess hydrogen together with the hydrogen produced in said other reaction to the first reaction for continuance of the process.

19. In a process of manufacturing pipeline quality gas, the steps comprising, arranging two reaction zones in direct heat transfer relation, feeding carbonaceous solid fuel and hydrogen into one zone, driving off volatiles while reacting hydrogen with the residual carbonaceous fuel in the presence of an excess amount of hydrogen to produce methane at a temperature and pressure which produces a product gas consisting essentially of methane and hydrogen, continually circulating said carbonaceous fuel into and out of said one zone and adding fresh carbonaceous fuel to said circulating fuel to replace that being consumed in the reaction with hydrogen, collecting said product gas, reacting a portion of the methane of said product gas with steam in the other reaction zone, at a temperature below the temperature in said one zone, to produce hydrogen, reacting carbon monoxide present in

the system with steam to produce hydrogen, the amounts of hydrogen thus produced being sufficient to replace the hydrogen being consumed in the first zone, the available exothermic heat from the first reaction zone being utilized to supply to said other reaction zone at least a substantial part of the endothermic heat required to produce hydrogen therein, separating out at least a portion of substantially only the methane which is produced in the first zone, collecting the same, and returning the hydrogen of said product gas together with the newly formed 10 hydrogen, to the first zone to continue the process.
